PERMUTATION LOCK CONTAINER

Silas A. Pierce, Jr., Pawtucket, R. I.

Application October 8, 1945, Serial No. 621,131

8 Claims. (Cl. 70—298)

1

My invention relates to improvements in containers and particularly to permutation locks for said containers.

An object of my invention is to modify the elements of large permutation locks for safes and other containers to provide a lock which is compact and takes up such small compass that it can be readily substantially concealed in the wall of the container itself without thickening said wall to any abnormal degree.

A further object of my invention is to embody the principles of a permutation lock with a self-closing latch. I preferably employ a simple pivoting latch which is normally urged to a closed position and a permutation lock normally retaining said latch in latched position, but in which the permutation locking members are movable to positions permitting unlatching of said latch.

A further object of my invention therefore, is to provide a permutation lock which becomes automatically closed and locked when the permutation members are out of permuted alignment when the cover of the box is merely closed.

To this end, instead of the rotatable tumbler members normally used in permutation locks, I provide a plurality of preferably closely nested slideable permutation members which may be readily concealed in a wall of the box and which have handles operable from the exterior of the box which may be selectively set in relative permuted arrangement to permit unlatching of the latch.

A further object of my invention is to provide a latch and a lever for operating said latch, both of which may pivot in a parallel plane parallel to the wall of the box on which they are mounted.

A further object of my invention is to provide a permutation lock which while preferably adapted for use on a small school or other box may be used on larger containers, and a further feature of my invention, which I believe is also applicable to all sorts of permutation locks is the novel means I employ to prevent an unauthorized opener of the box from working out the combination by manipulation of the permutation members, by chamfering the edges of their notches so that a manipulator, cannot detect a notch by moving the permutation members back and forth so that the locking element may strike against an edge thereof.

A further object of my invention, particularly when used as a school or other small box is to provide a permutation lock which will not only lock the box but also will lock a slideable drawer

2

in closed position within said box. This drawer may be provided with a cover so as to provide a valuable drawer for keeping money or other keepsakes or treasures of the school child from the other contents of the box, such as books.

These and other objects of my invention as may hereinafter appear will be best understood from the description of the accompanying drawings which illustrate an embodiment thereof.

10 In the drawings, Fig. 1 is a perspective view of a school box constructed in accordance with my invention in closed position with the closed cover also retaining a drawer in closed position.

Fig. 2 is a perspective view of the box shown in Fig. 1 with the cover retracted to open position and the drawer opened, with portions of the front wall of the cover being broken away to show the length of the slideable permutation members in the relative positions thereof shown in Fig. 1.

20 Fig. 3 is a sectional view of the closed box taken along the line 3—3 of Fig. 1.

Figs. 4, 5, and 6 are diagrammatic perspective views of the intrinsic parts of my improved permutation lock in assembled relationship including the latch, the latch lever and the central portions of the slideable permutation members, Fig. 4 showing the lock in locked position with the notches of the permutation members moved

25 out of relative permuted alignment, Fig. 5 showing the notches of the slideable permutation members being moved into alignment to receive the locking arm of the latching lever after the handles thereof have been moved into the permuted position shown in Fig. 1, and Fig. 6 shows a finger lifting the operating arm of the latch lever to pivot the locking arm thereof within the aligned notches for unlatching the latch prior to lifting the cover to open position.

30 Fig. 7 is a front elevation of the latch and latch lever showing how the latch may pivot as the box closes to permit the locking pin in the box body to ride up the point of the latch into the latch notch against the pressure of the spring even when the latch lever is retained in locked position by the lower edges of the permutation members in the position shown in Fig. 4.

35 In the drawings, wherein like characters of reference generally indicate like parts throughout, 40 generally indicates a school box constructed in accordance with my invention. While I have shown my invention applied to a school box, it is obvious that the various features thereof may be applied to any type of container. The box comprises a box body 42 having the upstand-

ing rear wall 14, the upstanding front wall 16, and the upstanding end walls 18 and 20. In the embodiment shown, the front and end walls are provided with the upstanding lip 22 on the inner portions of the tops thereof.

As stated, one feature of my invention is to provide a box having a drawer which may be automatically locked in closed position when the box is closed. For this purpose one of said front and end walls 16, 18, or 20, as shown the end wall 20 has a cut away portion 24 of substantial length for a purpose to be described. The box 10 is also provided with a cover 26 having a rear wall 28 pivotably mounted, as by the hinges 30, on the rear wall 14 of said box body 12, having cooperating depending front and end walls 32, 34, and 36 respectively, also having a depending lip 38 adapted to overlap the lip 22 on the outer portions of the tops of the body walls. I also provide a drawer 40 slidable through said cut away portion 24 having an outer end wall 42 also having an upstanding lip 44 on the inner portion of the top thereof. Said drawer front wall 42 is movable to a closed position flush with said box body end wall 20 to bring their respective lips 44 and 22 into alignment so that on closing of said cover 26 its lip 38 will overlie the drawer lip 44 to contain the drawer 40 within the box. In the embodiment shown, I also provide a partition 46 separating the portion of the box body 48 interior of said cut away portion 24 from the remainder 50 of said box to provide a drawer compartment 52. The drawer compartment 52 may if desired, be provided with an inner end wall to limit the inward movement of the drawer 40. In the embodiment shown to more clearly separate the money or treasures of the child from the remainder of the box, I provide a cover 54 for said compartment 52 which may have a front edge 56 to abut the lip 44 to alternatively limit the inward movement of the drawer 40 within its compartment 52 which cover may have a mirrored upper surface. If desired, the depending lip 38 on the cover need not extend all the way around, but may only extend a sufficient distance over the exterior of the cover lip 44 to retain the cover in locked position within the box and the lip 22 may be omitted, if desired. It is obvious however that as the lips 22 and 38 extend all the way around the box, they will provide means for preventing insertion of a flat member between the box body and cover to unlatch the latch of my improved specific type of permutation lock about to be described.

So far as I am aware, however, I am the first to provide means on the cover of a box to cooperate with means on the drawer when slidable to a closed position within said box to permit locking of the box cover to also lock the drawer within the box.

As stated, I employ a permutation lock for locking the cover 26 to the body 12 of the box. While my improved permutation lock is contained in such small compass that it may be ideally incorporated in the wall of a small box such as the school box shown, it is apparent that various features thereof, may be employed in any box or container. The elements of my improved permutation lock comprise latch means 58 to latch the cover 26 to the box body 12, locking means 60 for said latch means having an operating portion 62 movable from without said box and a locking arm 64, in the embodiment shown comprising the latch lever 60, and a plurality of 75 of spring may be employed or that other means

preferably nested slidable permutation members 66 having portions namely the lower edges 68 thereof abutting said locking arm 64 to retain said latch in locked position and having notches 70 adapted when brought into predetermined permuted relative positions to permit pivoting of said locking arm 64 through said aligned notches 70 to permit said locking means 60 to tilt said latch 58 to an open position on movement of said operating portion 62. The permutation members are relatively slidable along the front wall 32 of the box cover 26. The front wall of said box cover is preferably provided with the vertical operating slot 72 and the top wall 37 of said cover is preferably provided with the longitudinal slide slot 74 and the graduations on scales 76 adjacent said slide slot. Each slide member 66 is provided with an operating handle 78 projecting upwardly through said operating slot 74. It is thus obvious that the slidable members 66 form a unit as they are in closely nested relationship so that the handles 78 thereof may project through the top wall 37 of the box through a single slot 74 opposite the graduated scale 76.

In the preferred embodiment shown, the various parts of the permutation lock hitherto described are specifically constructed and assembled within the box or other container 10 as follows: The box body is provided with the latching pin 80 projecting inwardly from the front wall thereof if desired, as shown across a slot 82 projecting downwardly from the top of said front wall thus making said locking pin extend horizontally rearwardly at right angles to the locking arm of the latch 58. The rear portion of the front wall 32 of the box cover 26 is provided with a central cut out portion 84 extending at least partially through the top wall of the box and channels 86 extending laterally of said cut out portion 84 in the upper portion of said rear wall. The front wall 32 as stated, has the vertical operating arm slot 72 through it extending to said cut away portion 84 substantially centrally thereof. The top wall 37 of the cover is provided with a channel 88 extending lengthwise thereof above the cut away portion 84 and channels 86 in said front wall and as stated, has the slide slot 74 extending substantially equi-distantly of said operating slot. As stated, the graduations 76 comprising a scale containing any desired numerals, letters or characters are provided on said cover adjacent said operating slot. The latch 58 is pivotably mounted in any suitable manner as by the screw 90, in the cut out portion 84 of the front wall of the cover to pivot parallel to the wall of the cover and is provided with the depending latching work arm 59 having a notch 61 in one side thereof and a point portion 63 tapering from below said notch 61 to the opposite side 65 of said arm and a power arm 67 projecting laterally therefrom having a lip 69 projecting forwardly thereof. A normally straight spring 71 extends from the top of said latch preferably from the power arm 67 thereof to a fixed point 73 of said cover. In the embodiment shown said spring 71 has one end thereof soldered or otherwise secured to said power arm 67 and the opposite end 73 underlying the pin 75 projecting rearwardly from said cover front wall within the cut out portion 84 and may if desired, have its end fixed by projecting within said wall. While I have shown a resilient wire spring for this purpose, it is obvious that any suitable type

may be employed to normally urge the latch member 58 to a closed position. Said spring normally urges said power arm 67 to a position bringing said latching arm 59 into a substantially vertical position with the latching pin 80 engaged in the notch 61 thereof. Said spring 71 therefore is yieldable to permit said latching pin 80 to ride up the inclined point portion 63 of the latch 58 into the notch 61 to permit automatic latching on closing of said cover. As stated, the latch lever 60 is also pivotably mounted on said cover to pivot parallel to said latch 58 to abut said latch lip 69 to pivot said latch 58 to unlatched position in the embodiment shown being mounted on the same pivot screw 90. As stated, the latch lever or locking means is provided with an operating arm 62 projecting forwardly through said arm slot 72 and a locking arm 64 projecting rearwardly therefrom.

A plurality of nested aligned spacers 92 are mounted in the compartment 94 formed by the longitudinal channels 88 and 86 formed in the top wall and upper portion of the front wall of said cover to provide with the walls of said compartment nested slide guide ways 95 above said locking arm 64. The fixed spacers are provided with the aligned notches 96 in the lower edges thereof. The slide members 66a, 66b, and 66c as shown in Fig. 2 are preferably of a less length than the length of the cover 26 less the length of the slide slot 14 and are each mounted in one of said guide ways 95 and each have the notches 70a, 70b, and 70c in different portions of the lower edges 68 thereof. The respective handle lugs 78a, 78b, and 78c project upwardly substantially centrally of said respective slide members 66a, 66b, 66c through said single slide slot 14. If desired, the handle lugs 78a and 78c taper outwardly in the manner shown for ease of manipulation of the finger of the operator, laterally of the slot 14. For easy disassembly one end of the slot may be provided with the opening 98 for removing the handle lugs 78 selectively through the slot 14.

It is thus obvious that the slidable permutation members 66a, 66b, and 66c are laterally slidable within the respective guide ways 95 formed between the guide members 92 and walls of said channels in said cover and cover plate 100 to be described. With this construction, it is obvious that the lower edges 68 of said slidable permutation members 66a, 66b, and 66c normally abut said latch lever locking arm 64 as shown in Fig. 4 to positively prevent operation of the latch lever thereby retaining the latch in latched position. As shown in Figs. 1 and 5, however, when each of the respective handles 78a, 78b, and 78c are moved opposite predetermined graduated numbers on said scale 96 all the respective notches 70a, 70b, and 70c are brought into alignment with the notches 96 in the spacers and with each other to permit the locking arm 64 of the latch lever or locking means to pivot upwardly on upward movement of said operating arm 62 through the composite notch formed thereby to tilt said latch 58 including the notch 61 thereof away from said latching pin 80 to permit raising of the cover 26. Fig. 5 shows the notches 70a, 70b, and 70c brought into alignment with the notches 96 and Fig. 6 shows a finger raising the operating arm 62 to bring the locking arm 64 of the latch upwards within the composite groove formed by said aligned notches 70a, 70b, and 70c and 96. It is thus apparent that the handles 78a, 78b, and 78c for the slidable per-

mutation members must be moved into the desired predetermined relationship on the graduated scale to permit unlatching of said latch, but that once the latch is latched whether they are in this position or moved out of this position, the cover will automatically latch in the manner shown in Fig. 7 even with the notches 70a, 70b, and 70c out of alignment. After the box is once opened to lock the device, it is obvious it is necessary to move the handles out of alignment to permit the lower edges 68 of the permutation slide members 66a, 66b, and 66c to abut the locking arm 64 to prevent the latch 58 from being unlatched.

In the embodiment shown, I provide the cover plate 100 for the rear surface of said cover front wall 32 to complete the compartment 95 and retain said spacers 92 and slide members 66 within said compartment. It is apparent that said cover plate retains said spacers and slide members within said compartment in use. Said plate 100 may have an extension 102 underlying the cut out portion 84 of the front wall 32 which has an open portion 104 for the lateral pivotable movement of the latch arm 59 therein.

As stated hitherto, the guide ways may be provided in any suitable manner and the spacers 92 omitted, if desired. The channels 86 and 88 may also be omitted to have the entire slides function in rear of the front wall 32 of the cover and if desired, the slide members 66 may function at any desired distance from each other although for compactness I much prefer the nested arrangement shown. It is obvious that the notches 70a, 70b, and 70c may be formed in different portions of the slidable members 66 to achieve different combinations. Several different permutations, however, may be attained by reversing the positions of the slides in the compartment.

It is apparent therefore, that I have provided a novel type of box particularly adapted for a school box and preferably equipped with a novel type of permutation lock and if desired, the elements of the permutation lock may be employed for locking other types of containers, with the advantages described above.

It is understood that my invention is not limited to the specific embodiment shown and that various deviations thereof may be made without departing from the spirit and scope of the appended claims.

What I claim is:

1. A permutation lock for a box, having a box body having a latching pin projecting inwardly of the front wall thereof, and a cover for said box body pivotably mounted on the rear wall of said box body having a front wall having a vertical operating arm slot through said wall substantially centrally thereof, a top wall having a slide slot therein extending substantially equidistantly of said operating slot, and graduations on said cover adjacent said slide slot, comprising a latch pivotably mountable on the front wall of said cover to pivot parallel thereto having a latching work arm having a notch in one side thereof and a point portion tapering from below said notch to the opposite side thereof and a power arm projecting laterally therefrom having a lip projecting upwardly therefrom, a normally straight spring adapted to extend from said latch to a fixed point in said cover urging said power arm to a position bringing said latching arm into a substantially vertical position with said latching pin engaged in the notch thereof, yieldable to permit said latching pin to ride up said inclined point por-

tion into said notch to permit automatic latching on closing of said cover, a latch lever also pivotably mountable on said cover to pivot parallel to said latch to abut said latch lip to pivot said latch to an unlatched position, having an operating arm adapted to project forwardly through said arm slot and a locking arm projecting rearwardly therefrom, a plurality of nested aligned spacers mountable in rear of the front wall of the cover to provide nested slide guide ways above said locking arm, said spacers having aligned notches in the lower edges thereof, and a plurality of permutation slide members each mountable in one of said guide ways having notches in different portions of the lower edges thereof and handle lugs adapted to project upwardly substantially centrally thereof through said cover slide slot whereby the lower edges thereof normally abut said latch lever locking arm to retain the latch in locked position and when each of said handles are moved opposite predetermined graduations all of said notches are brought into alignment permitting the locking arm to pivot upwardly on upward movement of said operating arm, tilting said latch notch away from said latching pin to permit raising of said cover.

2. A permutation lock for a box having a box body and a cover pivotably mounted on said box body, comprising tilttable means to latch said cover to said box body normally spring urged to a latching position, locking means for said latch means having an operating portion movable from without said box and a locking arm, said locking means and latching means being so shaped that movement of said locking means will cause a tilting movement of said latching means, and a plurality of nested slidable members having portions normally abutting said locking arm to retain said latch in locked position and having notches therein adapted when brought into alignment when said slide members are brought into predetermined permuted relative positions to permit pivoting of said locking arm through said aligned notches to permit said locking means to tilt said latch to an open position on movement of said operating portion.

3. A permutation lock for a box having a box body and a cover pivotably mounted on said box body, comprising tilttable means to latch said cover to said box body normally spring urged to a latching position, locking means for said latch means having an operating portion movable from without said box and a locking arm, said locking means and latching means being so shaped that movement of said locking means will cause a tilting movement of said latching means, and a plurality of slidable members having portions normally abutting said locking arm to retain said latch in locked position and having notches therein adapted when brought into alignment when said slide members are brought into predetermined permuted relative positions to permit pivoting of said locking arm through said aligned notches to permit said locking means to tilt said latch to an open position on movement of said operating portion.

4. A permutation lock for a box comprising a box body and a cover pivotably mounted on said box body, comprising tilttable means to latch said cover to said box body normally urged to a latching position, locking means for said latch means having an operating portion movable from without said box and a locking arm, said locking means and latching means being so shaped that movement of said locking means will cause a tilt-

ing movement of said latching means, and a plurality of permutation members having portions normally abutting said locking arm and having notches therein adapted when brought into alignment when said permutation members are moved into predetermined permuted relative positions to permit pivoting of said locking arm through said composite aligned notches to permit said operating portion to move said locking means to tilt said latch means to an open position.

5. A permutation lock for a box comprising a box body and a cover pivotably mounted on said box body, comprising tilttable means to latch said cover to said box body normally urged to a latching position, said locking means and latching means being so shaped that movement of said locking means will cause a tilting movement of said latching means, locking means for said latch means having an operating portion movable from without said box and a plurality of permutation members adapted when moved into predetermined permuted relative positions to permit said operating portion to move said locking means to tilt said latch means to an open position.

6. A box comprising a box body, and a cover pivotably mounted on said box body, tilttable means to latch said cover to said box body normally urged to a latching position, locking means for said latch means having an operating portion movable from without said box and a locking arm, a plurality of nested slidable members having portions normally abutting said locking arm, said locking means and latching means being so shaped that movement of said locking means will cause a tilting movement of said latching means, and having notches therein adapted when brought into alignment when said slide members are brought into predetermined permuted relative positions to permit pivoting of said locking arm through said composite aligned notches to permit said operating portion to move said locking means to tilt said latch means to an open position, said slide members having handles extending in nested relationship through a single slot in said box, and graduations on the exterior of said box adjacent said slot.

7. A box comprising a box body, and a cover pivotably mounted on said box body, tilttable means to latch said cover to said box body normally urged to a latching position, locking means for said latch means having an operating portion movable from without said box and a locking arm, a plurality of slidable members having portions normally abutting said locking arm, said locking means and latching means being so shaped that movement of said locking means will cause a tilting movement of said latching means, and having notches therein adapted when brought into alignment when said slide members are brought into predetermined permuted relative positions to permit pivoting of said locking arm through said composite aligned notches to permit said operating portion to move said locking means to tilt said latch means to an open position, said slide members having handles extending through slot means in said box, and graduations on the exterior of said box adjacent said slot means.

8. A permutation lock for a box, having a box body having a latching pin projecting inwardly of the front wall thereof, and a cover for said box body pivotably mounted on the rear wall of said box body having a front wall having a vertical operating arm slot through said wall substantially centrally thereof, a top wall having a single slide

slot therein extending substantially equi-distantly of said operating slot, and graduations on said cover adjacent said slide slot, comprising a latch pivotably mountable on the front wall of said cover to pivot parallel thereto having a 5 latching work arm having a notch in one side thereof and a point portion tapering from below said notch to the opposite side thereof and a power arm projecting laterally therefrom having a lip projecting forwardly thereof, a normally 10 straight spring adapted to extend from said latch to a fixed point in said cover urging said power arm to a position bringing said latching arm into a substantially vertical position with said latching pin engaged in the notch thereof, yieldable to permit said latching pin to ride up 15 said inclined point portion into said notch to permit automatic latching on closing of said cover, a latch lever also pivotably mountable on said cover to pivot parallel to said latch to abut said latch lip to pivot said latch to an unlatched position, having an operating arm adapted to project forwardly through said arm slot and a locking arm projecting rearwardly therefrom, and a plurality of nested permutation slide members, mounted in rear of the front wall 20 of the cover, having notches in different portions of the lower edges thereof and handle lugs adapted to project upwardly substantially centrally thereof through said cover slide slot where- 25

10
